(57) **CLAIM**

The ornamental design for a pet waste container, as shown and described.

DESCRIPTION

FIG. 1 is a top left perspective view of a pet waste container showing the base and the container separated;

FIG. 2 is a side elevation thereof;

FIG. 3 is a front elevation thereof;

FIG. 4 is a bottom plan view of the container, with the base removed for convenience of illustration; and,

FIG. 5 is a top plan view thereof.
